DISTILLATION PROCESS

Jesse S. Walton, Westfield, N. J., assignor to
Standard Oil Development Company, a cor-
poration of Delaware

Application July 29, 1939, Serial No. 287,271

1 Claim. (Cl. 196—48)

The present invention relates to an improved method for the distillation of oils. The invention is concerned with a distillation operation in which loss of fresh feed into side streams is prevented. The invention is especially directed to a process in which vapors from a petroleum oil cracking operation are segregated, one portion entering a distillation tower from which side streams free of fresh feed are withdrawn, while the other portion enters a tower where it is contacted with fresh feed.

It is well known in the art to distill oils, particularly petroleum oils, by various processes under wide temperature and pressure conditions. It is also known in the art to subject petroleum oils to elevated temperatures and pressures, as for example, in the conversion of petroleum oils into relatively higher boiling and into relatively lower boiling fractions. In these oil cracking processes the feed material is subjected to elevated temperature and pressure conditions for various time periods which are usually measured in terms of yield per unit throughput, hereinafter termed "conversion per pass." These various variable factors are optimumly adjusted and, to a large extent, are functions of the particular feed material being processed and upon the yields and quality of the products desired. In a typical petroleum oil cracking operation, the feed oil is introduced into the bottom of a primary bubble tower. Lighter portions of the feed oil are vaporized in said primary bubble tower and passed overhead with the cracked products. The remaining feed oil, together with cycle stock, is withdrawn from the bottom of the primary bubble tower and introduced into a furnace or heating coil in which the oil is heated to cracking temperatures. The heated oil is withdrawn from the heating coil, passed into a reaction or soaking drum in which the oil is held for an additional time under cracking conditions. The cracked oil is withdrawn from the reaction drum and then passed through a pressure release valve into an evaporator. Tar is usually withdrawn from the bottom of the evaporator, while the vaporized products are passed into the primary bubble tower in which they contact the fresh feed oil. The cracked vaporous products, together with vaporized portions of the feed oil, are removed overhead from the primary bubble tower and introduced into a secondary bubble tower. Temperature and pressure conditions of the system are usually controlled so as to remove overhead from the secondary tower a petroleum fraction boiling in the gasoline range. Heating oil

fractions are withdrawn from the bottom of said secondary bubble tower and may be recycled, but are preferably further refined and used as such.

The introduction of fresh feed into the primary tower as described results in material operating advantages. However, the operation is not entirely satisfactory since a considerable loss of fresh feed material occurs into the side streams. This is due primarily to the fact that lighter portions of the virgin feed oils are vaporized when they contact the hot oils from the heating coil.

I have now discovered a process by which it is possible in a cracking operation to recycle material withdrawn from the cracking system consisting of the most virgin materials, while at the same time to withdraw as a side stream for extraneous use a valuable by-product containing nothing but cyclic materials which have already been reacted.

The process of my invention may be readily understood by reference to the attached drawing which is given for the purpose of illustration and should not be construed as limiting the invention in any manner whatsoever. The figure illustrates my invention as applied to a typical petroleum oil cracking operation. It is assumed, for the purposes of description, that the feed oil is a petroleum gas oil fraction boiling in the range from about 400° F. to 700° F. The fresh feed oil is introduced by means of feed line 1 into the lower part of fractionating bubble tower 2 in which the fresh feed contacts cracked vaporous products which are introduced into bubble tower 2 by means of line 3. Lighter portions of the fresh feed, together with uncondensed portions of the cracked vaporous product, pass upwardly through tower 2 into a fractionating section. A side stream product is withdrawn from tower 2 by means of line 4, while the uncondensed vapors are removed from tower 2 by means of vapor line 5. The unvaporized fresh feed, together with cycle oil, is withdrawn from the bottom of bubble tower 2 and introduced into furnace 6 by means of line 7. Furnace 6 is designed to secure optimum heat transfer as the feed stock flows through tubes in the respective sections and to bring the oil up to the desired temperature. The total feed is withdrawn from furnace 6 by means of line 8 and passed into soaking drum or reaction chamber 9 in which the oil is held for an additional time period under cracking conditions. The cracked oil is withdrawn from reaction drum 9 by means of line 10 and passed through pressure release valve 11 into evaporator 12. The

flashed vapors pass overhead from evaporator 12 through line 13, while tar of the desired gravity is usually removed as a bottoms from evaporator 12 by means of line 14. This product may be cooled to the desired extent by means of cooler 30. The vaporous product leaving the evaporator 12 by means of line 13 is separated into two portions which enter towers 2 and 15. The amount of vaporous products distributed to the respective towers 2 and 15 is controlled by adjusting valves 16 and 17. The vaporous product entering tower 15 is subjected to fractionation from reflux entering tower 15 through line 18. Temperature and pressure conditions are adjusted on tower 15 to produce a bottoms heating oil cut of the desired specification which is removed by means of line 19. Conditions are also adjusted on tower 15 so that a side stream cut may be removed by means of line 20. Unde- 15 nensed vapors of the desired end point are removed overhead from tower 15 and introduced into secondary bubble tower 21 by means of line 22. Temperature and pressure conditions are adjusted in secondary tower 21 so that a petroleum fraction boiling in the gasoline range is removed overhead by means of line 23. This fraction is condensed in cooler 25 and passed to distillate drum 24 in which the fixed gas is separated by means of line 26, while the distillate is removed by means of line 27. The bottoms from tower 21 are removed by means of line 28 and may be recycled as reflux by means of line 18. The vaporous product from evaporator 12 introduced into tower 2 is subjected to temperature and pressure conditions so that a petroleum fraction boiling in the gasoline range is removed overhead by means of line 5. This fraction is preferably combined with the fraction removed overhead from tower 15 and led to secondary tower 21 operated in the manner described above. The bottoms from tower 2 comprising fresh feed and cycle stock are recycled through the cracking system. A petroleum fraction suitable for a clean cracking operation may be removed from tower 2 by means of line 4.

It is to be noted that all vapors entering tower 15 are originally present in the material entering furnace 6 and, therefore, pass at least once through the cracking zone. That portion of the vapors from line 13 which does not enter tower 15 is led to tower 2 in which the fresh feed serves to fractionate the vaporous product, the vapors imparting a portion of sensible and latent heat to the fresh feed, which fresh feed subsequently leaves tower 2 partially through line 4 and partially through line 7 along with the cyclic material. Any material leaving tower 2 through line 4 will contain certain fractions of the fresh feed which have been vaporized and, therefore, this side stream material will cause the loss of fresh feed fraction if it were to be withdrawn from the system as heating oil or some other by-product. For this reason, this invention contemplates that this side stream material leaving tower 2 through line 4 be cracked. Since this material will comprise a clean, well fractionated stock, it can be cracked at high temperatures and at high conversion per pass with freedom from coke formation. That portion of the fresh feed which is not vaporized in tower 2 will drop 70 into the bottom of the tower and is withdrawn through line 7, along with any reflux condensate formed in tower 2 by reflux entering through line 29. Since the material leaving tower 2 through line 7 consists of a relatively high boil-

ing material, it is cracked at lower temperatures than the material leaving tower 2 through line 4.

In accordance with the process of the present invention, the material leaving tower 15 through line 20 contains no virgin fresh feed fractions and, therefore, would not be a first class cracking stock but should be entirely suitable as a heating oil, whereas the material withdrawn from tower 2 through line 4 does contain a certain proportion of virgin fractions and consequently would be entirely suitable for a cracking stock. Likewise, any material leaving tower 15 through line 19 would contain no fresh feed fractions, whereas the material leaving tower 2 through line 7 would contain fresh feed fractions and is very suitable as a cracking stock. This invention contemplates, however, that it might be desirable to crack not only the material leaving tower 2 through lines 4 and 7, but also materials leaving tower 15 through lines 20 and 19.

The broad field of this invention can be said to embrace all distilling operations wherein a recycling procedure is used, and portions of the recycle stock withdrawn for use extraneous from the system. This invention would be applicable in the broad sense to any such procedure outlined above whenever it would be undesirable to have the side streams withdrawn contain any portions of fresh feed introduced into the system.

The particular field for the invention may be said to be limited to a cracking operation wherein side streams are withdrawn from the fractionating system, following the cracking operation, and when such side streams should preferably contain no virgin fresh feed materials.

An advantage of the system described here is that in this cracking or recycling operation, the material withdrawn from the fractionating system to be reacted always consists of the most virgin materials, and the stocks withdrawn as side streams for extraneous use contain nothing but cyclic materials which have already been reacted at least one time.

A further advantage gained by carrying out an operation such as is described here is that maximum selectivity of cracking stocks is secured with no contamination of heating oil streams with high quality virgin materials.

The process of the present invention is not to be limited by any theory or mode of operation, but only in and by the following claim in which it is desired to claim all novelty in so far as the prior art permits.

I claim:

A method of converting higher boiling hydrocarbons to lower boiling hydrocarbons which comprises passing a relatively heavy hydrocarbon through a conversion zone at an elevated temperature to effect the desired extent of conversion, separating the products of conversion into vapors and liquid residue, splitting the vapors into two portions, fractionating one portion of vapors in a fractionating zone to separate condensate oil from overhead vapors, the condensate oil containing only constituents which have passed through said conversion zone and adapted for use as a heating oil, passing the other portion of reaction product vapors to a second fractionating zone and contacting them with fresh feed comprising a relatively heavy oil to separate light constituents from the feed and fractionating the last mentioned reaction product vapors to separate overhead vapors from condensate oil containing unvaporized constituents from the fresh

feed, passing the last mentioned condensate oil to said conversion zone and treating the overhead vapors from said fractionating zones to separate a light hydrocarbon mixture containing gasoline constituents, the overhead vapors from said fractionating zones being passed to a third fractionating zone and fractionated to separate

another condensate oil from a light hydrocarbon mixture containing gasoline constituents and passing the last mentioned condensate oil as reflux to at least one of said first two fractionating zones.

JESSE S. WALTON.
